UNITED STATES PATENT OFFICE.

IRA MACFARLAND, OF NEW YORK, N. Y.

ADVERTISING APPARATUS.

SPECIFICATION forming part of Letters Patent No. 633,871, dated September 26, 1899.

Application filed March 26, 1898. Serial No. 675,324. (No model.)

To all whom it may concern:

Be it known that I, IRA MACFARLAND, a citizen of the United States, and a resident of New York, in the county of New York and State of New York, have invented certain new and useful Improvements in Advertising Apparatus, of which the following is a specification.

My invention consists of an automatic advertising apparatus wherein and whereby a number of sign or advertising curtains on rods are separately carried over a drum which supports them, so that each successive curtain is brought to view and held in view a sufficient length of time for the reading of the sign or advertisement printed thereon or attached thereto.

The invention also consists in the employment of reversely-operating arms, which carry the curtain-rods and curtains over the drum, and in the combination therewith of a suitable motor and gearing.

The invention also consists of the construction, arrangement, and combination of parts, all as hereinafter described and claimed.

In the accompanying drawings, to which reference is made and which form a part of this specification, Figure 1 is a front elevation of my new advertising-machine as it appears complete, with a glass front. Fig. 2 is an enlarged detailed view of the upper portion of the apparatus with the front removed and showing the motor and switch as employed in Figs. 9 and 10. Fig. 3 is an elevation of one side of the frame of the machine, showing the preferred arrangement and operation of the motor and mechanism operated by the motor. Fig. 4 is a sectional elevation of the same. Fig. 5 is a detailed view of the reciprocating rod or rack, the latter being in position to operate an electric switch or cut-out. Figs. 6 and 7 are enlarged end views of the drum or cylinder over which the curtains are carried. Fig. 8 is an enlarged side view of one end of the drum slotted to allow the curtains to be removed and replaced on the drum. Fig. 9 is a side elevation of one side of the frame, showing the application of a reverse electric motor for operating the gearing. Fig. 10 shows the opposite side of the frame.

In the drawings, A represents an ornamen-

tal front or casing. This may be a hinged door provided with a glass front B. It is secured to a main frame comprising side uprights 23 and top and bottom pieces 45. The side uprights 23 are provided with corresponding keepers or ways 66, preferably inclined, which receive the plates or flanges 7, which are secured to the end plates 9, as shown in Figs. 6 and 7, and project at the ends of the drum 8, so that these keepers and plates not only hold the drum firmly in place in the frame, but allow the drum to be readily removed from and replaced in the frame. The said plates or flanges 7 are secured to the end plates 9 by soldering or brazing the edges of the flanges to the said end plates of the drum, or they may be secured by any other well-known means.

The drum 8 is closed at its ends by plates 99, which are set inward a short distance from the ends of the drum, so that the ends or edges of the drum constitute flanges 1010, on which the curtain-rods 1212 are held and on which they move one by one around the drum. The curtain-rods 1212 are by preference held on the flanges 10 by means of hooks or small open loops formed by folding over the ends of the rods. The lower side of the drum is by preference flattened and inclined, as shown in Figs. 6 and 7, in order to hold the curtain-rods in line with one another at the bottom of the drum and in order also that the whole number of curtain-rods will slide down by gravity as rapidly as they are taken up and carried around the drum. A retaining and letting-off device 13 is employed at one or both ends of the drum for letting off the curtain-rods singly and holding back, meanwhile, the row of rods in the rear, as illustrated in Figs. 6 and 7, which device in its preferred form of construction will be hereinafter described.

The drum 8 is provided with a central shaft 14, which projects through the end plates 9 at each end of the drum, and said drum is also provided with another shaft 15. The latter shaft 15 is provided at or near its center with one or more carriers for the curtains, preferably in the form of friction-rollers 16, the periphery or peripheries of which project through slots 17 slightly beyond the surface of the drum 8, so that when a curtain-rod is

lifted up past the carriers 16 the movement of the said carriers moves the fabric along to a point where it will drop bodily back of the drum. The carriers 16 are by preference 5 roughened or provided with a covering of soft india-rubber, and to increase the friction on the fabric I prefer to employ the weight or counter rollers 18, which rest upon the carriers 16 or upon the curtain while in transit. 10 The weight or counter rollers 18 are supported by a frame or bail 19, so that they are easily lifted up from contact with the curtain-rods 12 and permit the said rods to readily pass under them or between them and the 15 carrier-rolls 16.

The shaft 14 is provided with the carrier-arms 20 20, one at each end of the drum, which operate to carry the curtain-rods and curtains up over the drum. These arms reciprocate 20 from the position shown in dotted lines in Fig. 7 to the position shown in full lines in Fig. 6, and they carry up a curtain-rod and curtain with each sweep. During the return motion of the arms 20—that is, during the return from 25 the position shown in Fig. 6 to that shown in dotted lines in Fig. 7—the carrier-rollers 16 revolve in the direction shown by the arrow in Fig. 7—that is, while the arms 20 turn back toward the right the carriers 16 turn toward 30 the left. At all other times the carriers 16 may remain at rest.

The movement of the arms 20 for carrying the curtain-rods up over the drum is accomplished by a suitable motor and gearing. I 35 have here shown and I prefer to use an electric motor, though a weight or spring motor might be used, particularly for a continuously-operating apparatus; but where intermittent action is desired, depending upon the pressing 40 of a button, I design in all cases to use an electric motor, which may be supplied with current from small batteries or connected to electric-light service, if convenient. In the type of mechanism shown in Figs. 3, 4, 45 and 5 the motor 21 rotates without reversal, while in Figs. 2, 9, and 10 the motor itself is reversed for the back-and-forth action of the arms 20.

In Figs. 3, 4, and 5 a train of gearing 22, 50 connected with a gear-wheel 23 on the power-shaft 24, slowly rotates a shaft 25, provided with a crank 26, and this crank by means of a connecting-rod 27 reciprocates a rack 28, held in bearings or a way 29. The rack 28 55 engages with a gear-wheel 30 on the end of the shaft 14, journaled in the drum 8, so that with the reciprocation of the rack 28 rotary reciprocating action is imparted to the shaft 14 and to the curtain-carrying arm 20 for the 60 requisite distance. The end of the rack 28 terminates in a rod 31, which passes through a keeper 32, and just before this rod reaches the limit of its downward movement it strikes a switch or cut-out plate 33, which cuts off 65 the current from the electric motor and automatically stops the operation of the apparatus.

34 represents an electric push-button con-

nexion comprising a spring-plate 34^a, having a finger or knob 34^b and a permanent contact-plate 34^c, so that when the plate 34^a is 70 pushed into contact with plate 34^c current will pass and start the motor. At the outset the rod 31 will be lifted from the switch 33, and this will close with the plate 33^a and close the circuit, and the apparatus will 75 continue to operate until the rod 31 again breaks the current.

35 35^a represent binding-posts, to which the elements of the battery are connected. 35^a is connected to one pole of the motor by a 80 wire 36, while 35 is connected to the other pole by a wire 37, switch 33 33^a, and wire 38. The push-button is put in circuit when switch 33 is open by the wire 37, leading from switch 33 to plate 34^c, and wire 40, leading from 85 plate 34^a to the plate 33^a, and thereby connected to the above-mentioned wire 38.

As above mentioned, the arms 20 20 are rigidly connected to the shaft 14 and operate with it. The opposite movement of the carriers 16 is taken from the said shaft 14 by means of the gear-wheel 41, fast on the shaft 15, the gear-wheel 42, loose on the shaft 14, the small gear-wheel 43, fast on the shaft 14, and the pawl 54, pivoted to the gear-wheel 42 90 95 in position to engage with the teeth of the gear-wheel 43—that is, wheel 43 and pawl 44 constitute a clutch, so that when the arms 20 20 are descending the gear-wheel 53 through pawl 54, will turn the gear-wheel 42 in the direction of the arrow, Fig. 7, and rotate the gear-wheel 41 and shaft 15 in the opposite direction. When the arms 20 approach the limit of their return sweep, they operate the retaining and separating devices 13, so that 100 the front curtain-rod is moved out from the rest, and at this time the ends of the arms 20 20, being sufficiently beveled at the ends for the purpose, spring past or engage the same, ready to carry the rod up over the drum, 105 causing the finger 45 to be lifted clear of the adjacent curtain-rod and the finger 46 to be thrust down between the two first curtain-rods, thus separating out the first curtain-rod from the rest and at the same time holding back the others. The outer ends of the arms 20 by spring action flip past the ends of the curtain-rod separately, as above described, or otherwise engage with said rod, ready so that when the button is pressed the 110 arms will carry the rod and its attached curtain W, on which the sign or other matter is printed or attached, up over the drum or up into position between the carriers 16 and weight-rollers 18, which in their operation 115 will carry the curtain fully over the drum.

Various separating and retaining devices for the curtain-rods may be employed; but I prefer to use for each complete device a walking-beam 43, pivoted at 44, and provided 120 each side of the pivot with fingers 45 46, which project down through holes in the flange 7. A spring 47 normally holds the walking-beam 43 in the position shown in Fig.

6—that is, with its inner end elevated—so that the finger 45 will be thrust down so as to retain the curtain-rods and at the same time hold the finger 46 elevated above the curtain-rods. A stud 48 on each of the arms 20 is arranged to strike upon the spring 47 and to depress the same, as illustrated in Fig. 7, whereupon the inner end of the walking-beam 43 will be depressed, causing finger 45 to clear 10 away for the first curtain-rod and causing finger 46 to be thrust down between the first and second curtain-rods, as illustrated in Fig. 7. At this time arms 20 will flip back or otherwise engage the first curtain-rod, and as 15 soon as the button is pressed they will carry the same, with its curtain up, over the drum and allow springs 47 to reset the retaining and separating devices 13 back to the position shown in Fig. 6. In order to allow the curtain-rods and their curtains to be readily removed from and replaced upon the drum 8, I form in one end of the latter a slot 48^c, as 20 shown clearly in Fig. 8.

In the form of construction shown in Figs. 25 9 and 10 the motor 21 is electrically connected to a reversing-switch 50, which is operated by an arm 51 on the shaft 14 and a sliding curved rod 52 in the path of said arm and connected to the switch 50, so that the motor 21 and the train of gearing 22 are at the proper time reversed in their direction of rotation, thus rotarily reciprocating the arms 20 directly from and by reversing the motor. With this arrangement the wheels 41, 42, 30 and 53 and the pawl 54 are used as before and for the same purpose. The electric battery is connected to the binding-posts 55 and 56. The post 55 is connected by wire 57 to the arm 58 of the switch 50. The post 56 is 35 connected by wire 59 to the flange 6 or to any other part of the apparatus which will carry the current to the arm 51. The switch-arm 58 is yoked to the switch-arm 60 by a hard-rubber plate 61. This hard-rubber 40 plate is provided with a finger 62, which is connected to the sliding rod 52, held loosely in the bearings 63 63. The switch-arm 60 is by wire 64 connected to the commutator-brush 65 of the motor 21. The heads of the 45 screws 66 66, which connect the hard-rubber plate 61 to the switch-arms 58 60, serve as contact-points to four reversing-plates 67, 68, 69, and 70, which constitute the stationary portion of the switch 50. Plates 67 and 70 50 are both connected to a wire 71, which connects with the coil 72 of the motor 21. The plates 69 and 70 are connected to a wire 73, which is connected to a binding-post 74 of the motor 21. A segment-plate 75 is connected by a wire 76 to another binding-post 77 of the motor, which binding-post is connected by a wire 78 to the other commutator-brush 79 of the motor. The segment-plate 75 is surrounded by a series of spaced contact-plates 80 80, some or all of which are connected to the segment-plate 75 by removable metal plugs 81. By removing some of

these plugs the apparatus may be regulated to run slow, and by inserting them in greater numbers the apparatus may be run at a greater speed, so that the apparatus may be regulated as well to the power of the battery. If the battery is strong, remove some of the plugs 81 and if weak insert some or all of them. When a number of the plugs are removed, 75 the momentum of the apparatus will carry the arm 51, which rubs against the plates 80, past those plates which are cut out by the removal of the said plugs. The two first plates of the series 80 (marked 80^a 80^a) are connected 80 to a plate 82, which by a wire 83 is connected to a starting spring switch-plate 84, (see Fig. 2,) which stands in line with another spring switch-plate 85, which may be pressed into contact with plate 84 by a push-button 86. 85 The plate 85 is by a wire 87 connected to the wire 76, so that when the button 86 is pressed the current will flow and start the motor and the entire apparatus. The arm 51 is in a plane with the arms 20, and the starting-point 90 will be that shown in dotted lines in Fig. 7. When in this starting position, the arm 51 will have struck the curved switch-rod 52 and shoved the arms 58 60 into contact with switch-plates 67 69, which are the cut-out plates, so 95 that in this position no current flows to the motor. Now on pushing the button 86 the motor is started. The current passes from post 55 through wire 57 and arm 58 of the switch to one of the middle plates 68 or 69, 100 thence through wire 73, post 74 of the motor, and coil 72, and through wire 71 to the outside plates 67 and 70 of the switch, thence through arm 60, wire 64, binding-post 65 of the motor, thence through post 79, wire 78, 105 post 77, and wire 76 to plate 75, thence through the apparatus to wire 59 to the opposite binding-post 56, and the apparatus will continue in its forward movement until the arm 51 strikes the end 52^a of the switch-rod 52 and 110 shoves it back, setting the switch-arms 58 60 over onto the plates 68 70, thus reversing the motor and the whole apparatus. In the reverse movement the current flows along wire 57, arm 58, to the outside plates of the switch 115 67 70, through wire 71 to coil 72 of the motor, to binding-post 74, wire 73, to inside plates 68 69 of the switch, thence to arm 60 of the switch, thence through wire 64, post 65, post 79, wire 78, post 77, wire 76, to plate 75, and 120 thence through the apparatus to wire 59 to the opposite post 56. When arm 51 rests on either of the two plates 80^a 80^a, which are not connected with plate 75, the circuit is broken; but these plates are connected with the plate 125 82. By pressing the button 86 the current instead of passing wire 76 is shunted to wire 87 and plate 85, Fig. 2, which by the pressure on the button is connected with plate 84, and the current passes through plate 84 and wire 130 83, Fig. 10, to plate 82, which latter is connected with plates 80^a and 80^a, thence through arm 51 and through the apparatus and out through wire 59 to binding-post 56. This re-

verse movement will continue until the arm 51 strikes the opposite end 52^b of the curved rod 52 and shoves it back, thus returning the switch-arms 58 60 to the cut-out plates 67 69, 5 whereupon the apparatus will come to rest until the button 86 is again pressed, when the operation is again repeated.

88 represents an electromagnet, and 89 an armature therefor attached to a bent push-frame 90, the upper horizontal end of which is arranged to engage with the teeth of one of the gear-wheels in the train 22, so that in case the motor should at any time stand on the dead-center it would be started by throwing the magnet 88 into circuit. The throwing of the electromagnet 88 into circuit is accomplished by pressing the button 86 sufficiently to force the plate 91, which is in front of plate 85, into contact with the metal keeper 92. The battery for the magnet 88 is connected to binding-posts 93 94, Fig. 10, the post 93 being connected to the plate 91 by wire 95, the post 94 being connected to one pole of the magnet by wire 96, the other pole 25 of the battery being connected by wire 97 to the said metal keeper 92.

I do not limit myself to an intermittently-operating machine, as it is obvious that by omitting the switch 33 the machine will operate continuously, and the same would result by substituting a spring or weight motor for the electric motor.

Having thus described my invention, what I claim as new, and desire to secure by Letters 35 Patent, is—

1. In an advertising apparatus, a frame, gearing attached to said frame, a motor for operating said gearing, a support held in said frame, a series of curtain-rods held to slide

on said support, a carrier at the top of said support for shifting the curtains over said support and independent friction means operated by said gearing for sliding the curtain-rods one by one past the said carrier, substantially as described. 45

2. In an advertising apparatus a frame, a support provided with curtain-rods held in said support, gearing attached to said frame, a rack reciprocated by said gearing, a shaft journaled in said support geared to said rack 50 and arms operated by said shaft for sliding the curtain-rods on said support and auxiliary carriers geared to said shaft, substantially as described.

3. In an advertising apparatus, a drum, a series of curtain-rods adapted to slide around said drum, a shaft journaled in said drum, arms attached to said shaft for carrying the curtain-rods partially around the drum, a carrier located at the top of said drum, and gearing, substantially as described, for rotating said carrier toward the back of the drum while the said arms move in the opposite direction, substantially as described. 55

4. In an advertising apparatus, the drum 65 provided with a central shaft, a series of curtain-rods adapted to slide around said drum, arms 20 secured to said shaft, gearing for rotarily reciprocating said shaft, a let-off and retaining device operated by said arms consisting of a walking-beam 43, fingers 45 and 46 and spring 47 arranged to normally hold the finger 45 depressed, substantially as described. 70
